UNITED STATES PATENT OFFICE.

ALFRED G. F. KUROWSKI, OF BROOKLYN, NEW YORK, ASSIGNOR TO UNDERWOOD ELLIOTT FISHER COMPANY, OF NEW YORK, N. Y., A CORPORATION OF DELAWARE.

TYPEWRITING MACHINE.

Application filed March 7, 1924. Serial No. 697,476.

This invention relates to typewriting machines of the portable class, in which, for compactness and lightness, it is usual to employ three rows of keys, with provision 5 for operating three types by any key.

An object of the invention is to so arrange the parts of a front-strike two-shift typewriting machine, having forty-two type-bars and keys to correspond arranged in 10 four banks, that they will occupy a minimum of space without impairment of the efficiency of the machine.

Another object is to so connect the key-levers and type-bars that the movement of 15 the key-levers is transmitted to the type-bars with the leverage increasing gradually toward the side bars, thereby to compensate for the unfavorable position of said bars.

Another object is to so arrange the universal bar with respect to the type-bars, and to so connect the keys and type-bars, that the type-bars will engage the universal bar at the moment of greatest acceleration, while the leverage between the keys and 25 type-bars will steadily and rapidly increase from the moment of impact with the universal bar to the end of the stroke.

Other features and advantages will hereinafter appear.

30 In the accompanying drawings, Figure 1 is a longitudinal vertical section. Figure 2 is a partial plan view.

Figure 3 is a view of a portion of the machine looking from the front, with parts in 35 section.

Figures 4 and 5 are diagrammatic views, the former of a center key, and the latter of a side key, showing the keys in printing position and in rest position.

40 In the present embodiment of the invention, the improved typewriting machine comprises a main frame, composed of a rear plate 1, side plates 2 and 3, and a front plate 4, said front plate being slotted vertically, as shown at 5, to form a front comb for the key-levers 7. The key-levers are forty-two in number, to correspond with the type-bars, and they are pivotally mounted at their rear ends on a fulcrum rod 6. 45 The plate 1, aforementioned, is transversely slotted on its under side at regular intervals, to receive the rear ends of the key-levers 7, and said plate is also slotted longitudinally to receive the fulcrum rod 6 on which 50 the key-levers are pivoted. The fulcrum- 55

rod slot intersects all the transverse slots for the key-levers, and each key-lever has a substantially U-shaped slot in its upper edge for receiving the fulcrum rod. The key-levers are inserted in the transverse slots 60 from below, as shown, and they are held in engagement with the fulcrum rod by spring mechanism to be described.

Said mechanism comprises a coil spring 8 for each key-lever, each spring being connected at one end to the lever, as shown in Figure 1, and at the other to a tension plate 9. The tension plate 9 is hinged to leaves 10, which are secured to the rear face of the rear plate 1 in any suitable manner, as, 65 for instance, by screws as shown, and said plate extends from side to side of the machine frame, and is adjustable at its free edge, to simultaneously vary the tension of the springs. The plate is adjusted vertically 70 at its free edge by means of screws 11. These screws are threaded through bosses 12 on the tension plate into engagement with the top of the plate 1, and they are held in adjusted position by means of lock-nuts 13. 75 Each key-lever 7 extends beyond the comb 4, and at its free end it is provided with an upturned portion carrying a key 14, the keys being arranged in four banks as shown.

The typing system, which includes a 80 platen 15, a type-bar rest 17, and a type-bar segment 16 carrying forty-two type-bars 20, is arranged above the key-levers. The type-bars are pivoted on a fulcrum rod 19 held in the segment in the usual manner. The type-bars are of the usual construction, each 85 having an open slot to hook over the fulcrum rod 19. Each type-bar is provided with an arm or heel 21 by means of which it is connected to the corresponding key-lever, and the bars strike against an anvil 22 on the segment, the usual type-bar guide 23 being provided for insuring the correct 90 striking of the type on the platen. In the usual construction, the typing assembly is 95 so arranged that the type-bars are substantially horizontal when in rest position, and are substantially vertical when in printing position. The provision of forty-two type-bars, necessary in a two-shift machine, necessitates that the bars be longer. Were the 100 typing assembly arranged in the ordinary manner, the height would be increased by the amount of extra length of type-bar, as would also the depth from front to rear. 110

To compensate for the increased length of the type-bar without increase in the height or depth of the machine, the typing assembly is tilted or inclined to an extent such that the type-bar rest is brought to substantially the level of the platen, the segment being positioned at the lowest part in the assembly, and well below the type-bar rest. This tilting of the assembly materially reduces the distance between the bottom of the segment and the top of the machine, that is the plane at the top of the platen and type-bar rest.

The vertical height of the machine is still further reduced by offsetting the key-levers downwardly intermediate their ends, as indicated at 7^a, so that they will dip beneath the segment. The levers are sufficiently offset to pass beneath the segment and the connecting mechanism between the type-bars and the key-levers.

The key-levers are connected to the corresponding type-bars by connections, each of which includes a toggle. A series of bell-crank levers 25 is mounted on a common support 24 held transversely of the frame near the front thereof. This support is longitudinally slotted on its upper face to receive a fulcrum rod 26, and the support is provided with a series of transverse slots on its upper face, intersecting the longitudinal slot, the transverse slots being designed to receive the bell-cranks which are pivoted on the fulcrum rod 26. The transmitting arm 25 of each bell-crank is connected to the operating arm or heel of the adjacent type-bar by means of a link 27, each link being pivoted at one end to the arm of the bar and at the other to the outer end of the transmitting arm of the bell-crank. The other arm of each bell-crank is longitudinally slotted, as indicated at 28, each slot being designed to receive a laterally extending pin 29 on the adjacent key-lever 7. The pins 29 are shouldered, and they are slidable in the slots 28 of the bell-cranks. Each lever has a depending lug 31 with which the pin 29 is engaged, and it will be noticed that all of the key-levers arch above the common support 24 for the bell-cranks.

The bell-cranks are pivoted parallel with the key-levers, and the transmitting arms of the bell-cranks are bent laterally inward on each side of the center of the machine, and at an angle such that they are in approximate alignment with the links 27 which connect the arms to the type-bars. Referring to Figure 1, it will be seen that the key-levers are of considerable length, and are pivoted well up at the rear of the machine, at about the lowest part of the segment. The levers are arranged alongside each other in parallel relation, and they are so spaced that the connection between each side type-bar and its key-lever during the movement

of the key and bar moves in a vertical plane, which is perpendicular to the fulcrum of the type-bar. With this arrangement, when a key is depressed, the pull upon the type-bar is substantially perpendicular to the axis 70 upon which it swings, and binding and friction are eliminated.

The link 27 forms one member of what is, in effect, a toggle joint. The other member may be considered as the transmitting arm 25 of the bell-crank or as the operating arm of the type-bar. Thus, each connection between a key-lever 7 and a type-bar 20 includes a toggle joint. Referring to Figures 4 and 5, it will be noticed that in the rest position of the type-bars, the toggle is broken, the members being just out of alignment. This relation is maintained for all the type-bars, the angle between the links 27 and the transmitting arms 25 being substantially the same throughout the assembly. To maintain this relation, the transmitting arms 25 of the bell-cranks must rise toward the sides of the machine, since the fulcrums 19 of the type-bars are rising. The rise of 90 the transmitting arms 25 does not, however, equal the rise of the type-bar fulcrums 19, and the angle between the respective type-bar operating arms 21 and the connections 25-27 between the keys to which they are attached gradually becomes greater toward the sides of the machine. At the middle of the assembly, these angles are acute, and, at the sides, while they are still acute when the type-bars are in rest position, they are considerably wider than at the center.

The more nearly the angle between the length of the type-bar operating arm 21 and the swinging mechanism 25 connected therewith approaches a right angle, the less stress is required on the key to start or swing the type-bar. From the middle type-bars outward, the angle of divergence between the type-bars and the connections 25-27 with the key-levers gradually increases, so that a given pressure on the side keys will be more effectively applied than at the middle keys. Thus, the unfavorable position of the type-bars at the sides is compensated for.

The type-bars 20 at the sides are less subject to the action of gravity, swinging, as they do, through a plane inclined to the horizontal at approximately 60°. Hence, the gravitational reaction which assists in the 120 restoration of the middle bars to rest position is reduced to such an extent that the side bars are sluggish in movement. This tendency to sluggishness is usually corrected by the provision of stronger springs 8 for 125 restoring the side key-levers. Greater stress is required to operate the side bars 20 because of their unfavorable position, as above mentioned, and by providing the key-levers 14 with stronger springs, the stress required 130

to operate the keys is further increased, but the leverage between the key-levers and the type-bars is gradually increased from the center toward the sides of the machine, by 5 gradually widening the angle between the type-bar operating arms 21 and the toggles 27-25, so that a given pressure on the side keys would be more effectively applied in the swing of the type-bar than at the middle 10 bar. The link ends of the transmitting arms 25 gradually fall below the fulcrums of the type-bars towards the sides of the system.

The transmitting arms 25 of the bell-cranks are raised by lengthening them, as 15 indicated in Figures 3, 4 and 5, and also by making the angle between the elbow portions of the respective bell-cranks more acute. Said raising of the transmitting 20 arms 25 increases their stroke, and, in order that the dip of the keys 14 may be uniform, the operating arms or heels 21 of the side keys are lengthened to compensate for the increased stroke of the side bars. If the 25 lengthening of the operating arms or heels 21 were gradual from the center type-bars to the side bars, each bar would differ from all the remaining bars. This, however, is not essential, since the difference in the 30 width of the angle between the operating arm or heel 21 and the toggle 25-27 of any particular type-bar and the adjacent bar is slight. For this reason the bars 20 are divided into three sets, the bars of each set 35 being of the same length. The middle set or series is composed of twenty-two bars, eleven on each side of the center. The second set comprises six bars on each side of the middle set, and the third set comprises eight bars, four at each side, as 40 clearly shown in Figure 3.

In the present invention, the universal bar 32 controls the carriage-feeding in the usual manner, and is so positioned with respect 45 to the type-bars that it will be engaged by the bars at the moment of their greatest acceleration, and at the moment when the toggle 25-27, which is a part of the connection between the type-bar 20 and the key 50 14, is passing from a right angle to an obtuse angle, that is, when the members of the toggle are moving into alignment. At such movement, the stress upon the key commences to act upon the key with a leverage 55 increasing steadily and rapidly to the end of the printing stroke. Referring to Figure 1, it will be noticed that each type-bar has an extension 33 on its rear edge and adjacent the fulcrum, which will engage the 60 universal bar 32 when the type-bar is substantially vertical. At this moment the angle between the operating arm or heel 21 of the type-bar and the adjacent member of the toggle, that is, the link 27, is a right 65 angle. Further movement of the key-lever

associated therewith tends to enlarge the same, that is to bring the type-bar fulcrum 19, the end of the operating arm 21, and the end of the transmitting arm 25 of the bell-crank towards a straight line intersection of 70 the three pivotal points. During the movement of the type-bar, from the time the type-bar starts from rest position until it attains the position of Figure 1, there is acceleration, that is, increased speed with less 75 power. When the parts attain the position of Figure 1, the acceleration of the type-bar is at its highest, and with further movement there is relative decrease in speed, with increase in power. The arrangement is 80 such that at its start until it assumes a vertical position, the type-bar is not burdened in any manner by operating other parts. Thus the whole touch or impact at the key may be utilized to raise and set the type-bar in motion before it takes up and operates the escapement device. 85

The type-bars 20 are assisted in their initial or starting movement from rest position by the connections 29 between the key-levers 14 and the bell-cranks 25. The arms of the bell-cranks connected to the key-levers are arranged alike, each in such manner that the slot 28 inclines downwardly and rearwardly, presenting thus an inclined or cam surface to the pin 29 which co-operates therewith. When a key is depressed, the pin 29 slides along the slot wall 28 with a camming action that provides for an easy 95 start. 100

By increasing the leverage between the key-levers and type-bars at the sides of the machine, and by making such increase gradual, the same amount of pressure on any selected key will produce like results 105 at the attached type-bar throughout the assembly. The touch is thus made uniform, and equally alike for all of the keys.

Variations may be resorted to within the scope of the invention, and portions of the 110 improvements may be used without others.

Having thus described my invention, I claim:

1. In a typewriting machine, the combination with type-bars and keys for operating the same, of connections between the keys and bars, said connections including bell-cranks pivoted on a common axis, and links connecting the transmitting arms of the bell-cranks to the bars, the link ends 115 of said transmitting arms being above the fulcrums of the middle bars and gradually falling below the fulcrums toward the sides, whereby to widen the angle between the type-bars and the links. 120

2. In a typewriting machine, the combination with type-bars and keys for operating the same, of connections between the keys and bars, said connections including bell-cranks, and links connecting the trans- 130

mitting arms of the bell-crank to the bars, the link ends of said transmitting arms being above the fulcrums of the middle bars and gradually falling below the fulcrums to ward the sides, whereby to widen the angle between the type-bars and the links.

3. In a typewriting machine, the combination with type-bars and keys for operating the same, of connections between the 10 keys and bars, said connections including bell-crank pivoted on a common axis, and links connecting the transmitting arms of the bell-crank with the type-bars, the transmitting arms of the bell-crank rising gradually 15 ally toward the sides of the machine, but

gradually falling below the level of the fulcrums of the attached bars.

4. In a typewriting machine, the combination with type-bars and keys for operating the same, of connections between the keys and bars, said connections including bell-crank pivoted on a common axis, and links connecting the transmitting arms of the bell-crank with the type-bars, the transmitting arms of the bell-crank rising toward the sides of the machine to follow the rise of the type-bar fulcrums, but gradually falling below said fulcrums to increase the angle between the type-bars and the links. 20 25

ALFRED G. F. KUROWSKI.
